UNITED STATES PATENT OFFICE.

CARLOS BASTO, OF RIO DE JANEIRO, BRAZIL.

ELECTRIC TRAMWAY.

SPECIFICATION forming part of Letters Patent No. 319,947, dated June 16, 1885.

Application filed December 11, 1883. (No model.) Patented in Portugal August 23, 1882, No. 771, and in Brazil February 24, 1883, No. 16.

To all whom it may concern:

Be it known that I, CARLOS BASTO, a citizen of the Kingdom of Portugal, residing at Rio de Janeiro, Brazil, have invented certain 5 new and useful Improvements in Electrical Tramways, (the same having been patented to me in Portugal August 23, 1882, No. 771, and in Brazil February 24, 1883, No. 16;) and I hereby declare that the following is a full and 10 exact description thereof.

My invention consists in the arrangement of the electric conductors below the track in a small channel, the covering of which is provided with a narrow longitudinal slot or 15 groove, which permits the passage of the wire-carriers as well as of certain mechanisms which I prefer to employ in certain cases with a view to augment the adhesion of the traction-wheels upon the rails.

20 Certain portions of my invention are applicable to tramway-lines now in common use where the grades are not of such steepness as to render the traction by means of the natural adherence due to the weight of the cars and 25 their contents difficult or impossible, while certain other portions of the invention are particularly applicable to lines having steep grades, and constitute a peculiar system of tracks and of cars.

30 The accompanying drawings form a part of this specification, and represent what I consider the best means of carrying out my invention.

Figure 1 is a transverse section showing 35 one side of the track with the arrangement of the electric conductors and of those devices attached to the car which serve to lead the current to and from the motor placed on the car. This figure represents the invention as 40 adapted for use on tramways with ordinary grades. Fig. 2 is a cross-section showing a modification of the construction. The remaining figures show the invention as adapted for use on tramways with steep grades. 45 These represent the complete form of the invention. Fig. 3 is a side elevation, partly in section, of the track and the principal portions of a car. Fig. 4 is a plan of Fig. 3. Fig. 5 is a side elevation showing a car; and Fig. 6 50 is a transverse section of the track and the car as illustrated in Figs. 3, 4, and 5.

Referring to Fig. 1, a channel is formed in the ground just on the outside of one of the rails A. The walls B B' of this channel may be formed of masonry, concrete, or bricks, the 55 inner wall being built directly under the longitudinal sleeper C, which supports the rail A. This channel, which may be about one foot in width, is covered by large plates D, of stone or cast-iron, which are laid so as to leave a 60 groove or opening of about one inch in width between themselves and the rail A.

Under the extremities of the transverse sleepers E, which project beyond the lateral face of the longitudinal sleepers G, I arrange, 65 by means of iron yokes I and of L-pieces J, the electric conductors F, the form and arrangement of which may be varied at will. I prefer, however, the arrangement illustrated in the drawings, according to which longitudinal bars or small beams of wood or other non-conducting material are employed, which are formed with grooves of cylindrical cross-section opening downward, which grooves are 70 lined with copper, brass, or other good conducting material G, thus constituting two insulated conductors for the passage of the current from and back to any suitable source of electricity. The longitudinal bar or beam F is preferably formed of four parallel strips of 75 wood rendered water-proof by immersion in any suitable bath, and held together by means of fastenings similarly made water-proof, the whole being covered by means of a water-proof fabric, if such should be found desirable in 80 practice.

In order to still more efficiently prevent the passage of any portion or of the entire current from one conductor G to the other, I form in the center and along the entire length of the 90 compound bar or beam F a hollow space, as shown at g, whereby the insulation between the conductors is more completely attained.

At every crossing and at every bifurcation of the track the bars or beams F are interrupted and their opposite extremities are formed with funnel-shaped openings to facilitate the passage of the metallic conducting pieces carried on the car, and the metallic conductors G on one side of the break are connected with those on the other side by means of suitably-arranged and properly-insulated 95 100 rods.

conducting-wires (not shown) to complete the circuit along the entire track. This feature, however, forms no part of the present claim, and has not been illustrated.

- 5 The cars to be used in connection with this construction may be ordinary tramway-cars, provided with a dynamo or a magneto electric motor, which is connected with the axles of the wheels by any of the ordinary or suitable means. In addition to such motor, the car is provided on the side over the channel and between its axles with a stout frame of boiler-iron, H, which extends down through the slot K into the channel and is bent as shown.
- 5 Its lower portion carries a piece, N, of ebonite or other non-conducting material, which latter supports the two friction-pieces L, by means of which electric connection is established between the motor on the car and the conductors G. The friction-pieces L are made of brass, about one thirty-second of an inch thick, and bent into the shape of a cylinder of about six inches length and of a diameter to match the interior of the conductor G, and 5 formed near their centers with an extension, M, projecting downward and capable of sliding in the support N. The ends of the cylinders L are turned inward in the shape of a cone, and the cylinders are made elastic, so as to facilitate the easy sliding along of said cylinders in the conductors G.

In order to insure a sufficient frictional contact between the cylinders L and the interior of the conductors G, a system of expanding springs, R, is arranged within said cylinders, whereby the surface of the latter is held in contact with the conductors G, while at the same time sufficient play is allowed for their passage along curves.

The two friction-cylinders L are alike, and their vertical supports M are connected to the electric motor or the car by means of properly insulated conductors, which pass upward in suitable spaces formed in the supporting frame H.

It will be understood that the wheels of the car on the side of the channel may be formed without treads, in which case the upper portion of the frame H, down to within the slot K, should be made of sufficient strength and thickness, the slot K being slightly widened along the curves of the track.

In Fig. 2 I have represented a modification of the above-described arrangement, which is also well adapted for lines having but slight grades. In this figure the slot, which allows communication with the underground channel, is arranged in the line of one of the rails, and instead of a single rail on this side I employ two parallel rails, S S, which serve as rail and counter-rail, a slot, O, being left between the two rails. The whole is so proportioned that the two rails and the intervening slot do not exceed the width of an ordinary tramway-rail. Under this rail, at intervals of, say, three feet, are placed cast-iron shoes Q, which serve to determine the cross-section of

the channel, and at the same time to hold the two rails S S in place. One of the conductors T consists of a metallic cylinder, open at its lower portion and covered at its exterior with a suitable non-conducting material. In this case the conductor for the return of the current may be formed by either of the rails S S, or a conductor similar to T, and placed on the opposite side of the channel, may be employed, or a small rail, U, (shown in the drawings at the bottom of the channel,) may be used for the purpose.

Upon the small rail U rides a wheel, V, which is connected to the car by a frame of boiler-iron, X, (only partially represented in the drawings.) This wheel V carries a friction-piece, Y, which slides in the conductor T.

The channel is lined and covered with concrete, the ordinary paving being laid upon the latter. The shoes Q are connected by means of tie-rods Z with the longitudinal sleeper of wood or cast-iron W, upon which is fastened the second rail of the track. Figs. 3 to 6 show the arrangement which I prefer to use. This is adapted for cases where the track presents steep grades, where the adhesion of the driving-wheels upon the rails must be increased by artificial means. According to this arrangement the channel is placed in the center of the track, its walls being formed of masonry or concrete, or in any other suitable manner. The channel should have a width and depth of about eighteen to twenty inches. It is partially covered by cast-iron plates b, which will be described more in detail further on, and which are so laid as to leave a longitudinal slot or narrow opening in the center of the track. On each side of this slot are fixed, by means of screws, double-headed rails c, which form the traction-surface. The outer edges of the plates b constitute also the carrying-rails, or these edges, may if desired, be covered by an iron or steel rail.

It will be understood that the rails c are connected by means of screws or bolts to the adjacent portions of the plates b. The rails at the outer border may be fastened by means of spikes, whereby great stability is imparted to the entire system. As will be seen from the drawings, Fig. 6, the conductors are placed on both sides of the channel in insulating bricks d, which project from the masonry walls a on the upper side of the channel. For this purpose the bricks d have on their lower sides a cylindrical groove opening downward and lined on its interior with any suitable conducting metal, as in the above-described arrangements.

The car employed with this arrangement differs considerably from those heretofore used on tramways. The passengers are seated back to back. The width of the track, which is determined by the exterior edges of the cast-iron plates b, should not exceed three feet. The car has six wheels—three in front, one in the center, and two in the rear. The three front wheels are keyed upon a common axle, e, Figs.

3 and 4. The wheels on both sides carry no flanges, while the central wheel, *g*, is provided with a central projecting flange, which serves as a guide by entering into the slot formed in the center line of the track between the rails *c c*, Fig. 6. The single wheel *h* in the middle of the car is keyed to the center of the second axle, *l*, which receives its movement by any suitable connections from the front axle, *e*, which itself receives motion from the electric motor placed on the car, the power from the latter being transmitted by the aid of pulleys *i*. The rear axle, *j*, is fast, and carries the loose wheels *k*. Central wheels, *g* and *h*, have each a double tread bearing upon the two rails *c*, which form the sides of the slot, and the flange of the wheel *h*, which is keyed upon the second axle, *l*, is toothed, for purposes which will appear further on. Between the backs *m* of the seats of the car is arranged a frame, *n*, (see Figs. 3, 4, and 5,) which extends downward through the slot in the track into the interior of the channel, and which surrounds the central wheel, *h*, of the second axle, *l*. This frame *n* is spread in the channel, and supports another smaller wheel, *p*, having also a double tread and carrying a central toothed flange engaging with the similarly-toothed flange of the wheel *h*, from which it receives its motion. The frame *n* is supported by springs *o*, and carries eccentric-wheels *q*, with provisions for turning them, (see Fig. 3,) whereby the action of the springs *o*, and consequently the force with which the rails *c* are grasped between the upper and lower wheels, *h* and *p*, may be regulated, or the force taken off altogether. These two wheels, under the action of the springs *o*, serve to firmly clamp the rails *c* and thereby increase the hold or traction considerably on up and down grades. In the latter they constitute a brake. On those portions of the track which are quite or nearly level the brake *q* is operated to depress the frame *n*, and the car advances with the aid of adhesion due to the weight alone. The frame *n* serves also as a support for the two ebonite pieces which hold the supporting-rods of the friction-cylinders *r*, which latter are constructed in the same manner as those previously described, and perform the same important function of maintaining electrical contact with the respective conductors extending along in grooves, as before described.

Although the car arranged as indicated is not symmetrical at its extremities it may be caused to run in either direction upon the same track. For this purpose it is only necessary to provide at the ends of the line a return-curve; or I can, by providing a switch for reversing the connections of the current, run the car either end foremost, back and forward, without such turning.

The car, as shown, is particularly intended for transporting a small number of passengers—twelve at the most. A single attendant may guard the two lateral entrances of a single platform in front and also operate the brake. The sides of the car are provided with a railing so as to compel the passengers on boarding the car to pass the conductor.

By inserting glass windows the car may be adapted for use in winter.

The several channels in the roadway may have proper connections with the sewer or other drain in order to carry off water.

I claim as my invention—

1. In an electric-tramway system, the underground open channels having conducting linings *G*, insulated as described, combined with the elastic friction-pieces *L*, having extensions *M*, supported in piece *N*, the expanding-springs *R*, and electric connections with the car and motor, as set forth.

2. In combination with the underground channels, as described, and with the spring friction-pieces *L*, the wheels *h p*, frame *n*, means, as *q*, for adjusting the friction, and connections with the car, as and for the purposes set forth.

3. The combination, with the wheels *h p*, meshed, as shown, of the adjustable frame *n*, the springs *o*, for supporting the said frame *n*, the cams *q*, for adjusting the friction of wheel *p* upon the lower surface of the rail *c c*, the underground channel, and means, substantially as described, for making electrical connections therewith, as herein specified.

In testimony whereof I have signed this specification in the presence of two subscribing witnesses.

CARLOS BASTO.
